HANDLE FOR TOOLS

Edward H. Reymann, Bronxville, N. Y., assignor to Austenal, Inc., a corporation of New York

Application October 4, 1957, Serial No. 47,980

Term of patent 14 years

(Cl. D83—1)

FIG. 1

FIG. 2

FIG. 4

Fig. 1 is an elevation of a handle for tools embodying my new design;

Fig. 2 is a tool-end view of the handle;

Fig. 3 is a butt-end view of the handle; and

Fig. 4 is a perspective view of the handle.

I claim:

The ornamental design for a handle for tools, as shown.
